UNITED STATES PATENT OFFICE.

DAVID FERGUSON, OF PITTSBURGH, PENNSYLVANIA.

COKE-OVEN-CLEARING MECHANISM.

Application filed April 17, 1920. Serial No. 374,537.

To all whom it may concern:

Be it known that I, DAVID FERGUSON, a citizen of the United States, and a resident of Pittsburgh, in the county of Allegheny and State of Pennsylvania, have made a new and useful Invention in Coke-Oven-Clearing Mechanism, of which the following is a specification.

This invention relates to mechanisms for clearing coke ovens and has for an object to produce a simple and effective mechanism in which the entire coke drawing operation is accomplished by means of power driven apparatus.

15 A further object is the production of a power actuated coke drawing or similar apparatus which is simple and effective in operation and which may be manipulated and controlled by a single operator.

20 These and other objects, which will be made more apparent throughout the further description of the invention, are attained by means of a mechanism embodying the features herein described and illustrated in 25 the drawings accompanying and forming a part hereof.

In the drawings Figure 1 is a perspective view of a mechanism embodying my invention and shown in connection with a diagrammatic view of a coke oven, a track on which said mechanism is movably mounted and a fragmental view of a car into which said mechanism discharges. Figure 2 is a 30 side elevation of apparatus forming a detail of my invention and which is a slight modification of similar apparatus shown as a part of the mechanism illustrated in Figure 1. Figure 3 is a view illustrating a portion of the operating mechanism forming a 35 part of my invention.

40 Referring to the drawings:

The apparatus illustrated includes a frame 6 which is provided with wheels 7 adapted to run along a track 8. A carriage 9 is pivotally mounted on the frame and forms a support for a ram 10, which is movable longitudinally with relation to the carriage. The forward end of the ram carries a breaker 11, which is adapted to be moved into engagement with the mass of coke contained in

a coke oven and to break up the coke for the purpose of facilitating its removal from the oven. The ram also carries means for removing from the oven the particles of coke freed by the action of the breaker. 55 The means illustrated consists of members 12, similar to rakes, which are secured to endless chains carried by the ram and which are adapted to accomplish a raking action across the floor of the coke oven and to thereby deliver through the door of the oven the coke particles freed from the coked mass within the oven. The frame 7 also carries an apron 13 which is adapted to be moved adjacent to the lower edge of the oven door 60 and to form a slide over which material removed from the oven is delivered to a conveyer 14 mounted on the frame. A chute 15 is located at the delivery end of the conveyer and receives material delivered by the 65 conveyer and directs it into a car 16 or other receptacle. The mechanism illustrated is self-propelling along a track 8 and is provided with power actuated means for accomplishing this and also for advancing and withdrawing the ram, for actuating the breaker 11, the members 12 and the conveyer 14 and for swinging the carriage 9 to different positions with relation to the frame 6. 70

The frame 6 may be of any suitable construction and as illustrated is provided with four wheels 7 of the form ordinarily used in connection with railway cars. A carriage supporting superstructure is rigidly secured to the frame 6 and consists primarily of vertical uprights 17 which terminate in and are secured together by an arched top member 18. Cross struts 19 and 20 are secured to and extend between the uprights 17 and form a support for a king-pin block 21 80 which forms a part of the carriage 9, is located between the struts 19 and 20 and engages a king-pin 22, which is suitably secured to the struts 19 and 20 and pivotally secures the carriage 9 to the frame 6. As 85 illustrated, the carriage 9 includes two channel irons 23 and 23' which embrace and are rigidly secured to the king-pin block 21. These channels are also secured together, preferably in parallel relation, by means of 90 95 100

plates or other suitable tie members. The carriage also includes two pair of ram hangers 24, one pair mounted at the forward and the other at the rear end of the carriage. 5 Each of these hangers is secured at its upper end to one of the channels 23 or 23' and all the hangers co-operate in supporting the ram 10. As shown in Figure 1, the hangers of each pair are secured together by means 10 of cross bolts or tie members 25 which perform the double function of securing the hangers together and of supporting the ram.

The ram is preferably formed of two lateral and longitudinally extending channel members which are secured together by 15 means of a top plate 27 and other suitable stiffening or bracing members. The ram extends longitudinally of the carriage and is located between the tie rods 25 of each pair 20 of hangers. As shown in Figure 2, the lower tie rod 25 of each pair may be provided with rollers 28 on which the rack is supported, and the upper tie rods may be provided with similar rollers 29 which are adapted to engage 25 the upper face of the ram and thereby hold the ram against vertical displacement. In Figure 1 I have shown each hanger provided with a roller 29 so located and arranged as to engage a lateral face of the 30 ram. With this arrangement, the ram is held between two sets of such rollers and, therefore, lateral displacement is prevented.

As illustrated, the breaker 11 consists of 35 two sets of curved knives or prongs. Four such prongs are included in each set and the two sets are secured together by, or are mounted on a drum 31. As shown in Figure 1, each set of prongs is mounted on the axle of the drum 31 beyond the 40 supporting members 32 of the axle. Figure 2, however, shows the prongs secured to the drum 31. As illustrated, the members 32, in effect, form an extension of the ram, since they are secured to the forward end of 45 the lateral channels forming a part of the ram.

The breaker is actuated by means of two endless chains 33, each of which is carried 50 on a sprocket 34 journaled at the rear end of the ram and a sprocket 35 secured to or forming a part of the drum 31. The sprockets are so located and arranged that the chains are located in parallel relation 55 and extend the entire length of the ram. As shown, these chains co-operate in actuating the members 12.

Each member 12 consists of a rake-like head 37, an arm 38 and a supporting rod 39 preferably integrally formed with the 60 arm 38. Each end of the supporting rod 39 is pivotally secured to one of the chains 33 and the chains co-operate in moving the members 12 across the top plate 27 of the ram toward the breaker 11 and below the

ram away from the breaker. The pivotal support for each member permits the rake-like head 37 to drop into engagement with the floor of the coke oven after the member has moved across or around the drum 31.

The ram is provided with a rack 40 (see 70 Figure 2) which is engaged by a gear 41 and which co-operates with the gear in moving the ram longitudinally with relation to the carriage. As shown, the rack may be secured to one of the lateral members of 75 the ram in such a way that the lateral member forms a lateral shroud for it.

The chains 33 are driven by means of sprocket wheels 42, which are mounted on a shaft 43 journaled in suitable brackets 80 formed on or secured to the rear hangers 24. As shown in Figure 2, the sprocket 42 may be driven by a motor 44 which is mounted on the carriage 9 and which may receive power from a line-wire 45 through 85 a trolley 46, mounted on the arched support 18. As shown, the shaft of the motor is provided with a worm 47 which meshes with a worm wheel 48 mounted on a shaft 49. The shaft 49 is provided with a bevel gear 50, which meshes with a bevel gear 51 mounted on a shaft 52. The shaft 52 is journaled in suitable brackets carried by the hanger and is provided with two bevel gears 53 and 54, the first of which meshes with a 90 bevel gear which drives the gear 41 and the second of which meshes with a bevel gear 95 which drives the sprocket 42.

The pivotal motion of the carriage about the king-pin 22 is accomplished by means 100 of an arc-shaped rack 55 rigidly secured to the uprights 17 of the superstructure and a pinion 56 journaled on the carriage and driven by the motor 44 through the agency of bevel gears 57 and 58, a shaft 59 and bevel gears 60 and 61. It will, of course, be understood that a suitable clutch mechanism is employed between the shaft 52 and each of the bevel gears 53, 54 and 57, so that 105 the motor 44 is capable of independently operating the breaker 11 and the members 12, or of advancing and withdrawing the ram or of swinging the carriage about king-pin 22.

In Figure 3 I have illustrated such 110 clutch members. It will, of course, be understood that each of the gears in question is rotatably mounted on the shaft 52 and that the co-operating clutch member 65 is splined 115 to the shaft and is capable of being moved longitudinally thereof to engage or disengage its co-operating gear. It will also be understood that each member 65 may be operatively connected to a separate operating lever located at a convenient point near the operator's platform, so that the operator 120 may control the several functions of the ram. These operating levers and the connecting links are omitted for the sake of clearness.

The main frame 6 of the mechanism carries the conveyer 14. As shown, the conveyer includes two side members which are supported in parallel relation on the frame 6 and which support a large mesh screen or grill work 66, which secures the lateral members together and thereby stiffens the frame of the conveyer 14. A pair of sprockets 67 are located at the delivery end of the conveyer frame and a similar pair of sprockets 68 are located at the receiving end of the conveyer. Each pair of sprockets is mounted on a suitable shaft and each sprocket is located adjacent to one of the lateral members of the conveyer frame. These sprockets co-operate in mounting endless chains 69 which carry the conveyer cleats 70. It will, of course, be understood that any type of conveyer belt may be employed which is suitable for conveying relatively hot coke particles. An electric motor 71 is mounted on the frame 6 and is coupled or otherwise secured to a shaft 72 which extends transversely across the frame and carries a sprocket 73 for transmitting power to the propelling wheels 7 of the mechanism. A gear 74 for transmitting power to the conveyer 14 is also mounted on the shaft. The sprocket 73 is shown operatively connected to a sprocket 75 by means of a chain 76. The sprocket 75 is rigidly mounted on the axle of the propelling wheels 7. The gear 74 meshes with a gear 77 mounted on a stub-shaft on which a sprocket 78 is also mounted. The sprocket 78 is operatively connected to a sprocket 79 by means of a chain 80. The sprocket 79 is rigidly mounted on the shaft of the conveyer supporting sprockets 68. If it is desirable to transmit power directly to each pair of sprockets 67 and 68, the shaft of the sprockets 68 may be geared to the mounting shaft of the sprockets 67 by means of a shaft 82 and suitable bevel gears such as are illustrated at 83 in Figure 1.

The delivery chute or hopper 15 is shown suspended from extensions 84 secured to the delivery end of the conveyer 14. In the drawings I have shown a support 85 secured to one of the rear hangers 24. This support may be employed as an operator's platform or it may be employed as a support for a larger platform, which may extend between hangers of the front and rear sets.

It will, of course, be understood that each of the motors 44 and 71 is provided with a controller located in a convenient position with relation to the operator's platform and that the sprocket 73 and the gear 74 will be provided with clutches similar to the clutches illustrated in Figure 3, so that the motor 71 will be capable of independently driving the conveyer 14 or the wheel 7 of the mechanism. It will, of course,

be understood that the motor 71 receives current from the line-wire 45. 65

The operation of the apparatus is as follows:

The conveyer is moved to a position along the track 8 opposite to the coke oven from 70 which the coke is to be drawn. This is accomplished by operatively locking the sprocket 73 to the shaft 72 and by delivering current to the motor 71. As soon as the mechanism is in place, the clutch controlling the sprocket 73 is shifted for the purpose of rendering that sprocket inoperative as a power delivering agent and the clutch member associated with the gear 74 is moved to operatively lock that gear to 75 the shaft 72. This operatively connects the conveyer to the motor 47. The clutches associated with the gears 53, 54 and 57 (Figure 3) are then set so that the gear 53 is operatively coupled to the shaft 52, whereas, the other gears mentioned are operatively disconnected from the shaft. The motor 44 is then started in a direction to advance the ram through the open door of the coke oven. As soon as the ram is in the desired position, the clutch associated with the gear 53 is withdrawn and the clutch associated with the gear 54 is moved to the operative position. This transmits power to the breaker 11 and the members 12 through the agency of the sprockets 42 and chains 33. It will, of course, be apparent that it is desirable to so gear the driving mechanism of the chains 33 that the breaker may be placed in operation after advancing the ram without reversing the motor 44. The breaker is continually pressed into engagement with the mass of coke within the oven by advancing or by swinging the ram. As has been said, the swinging of the ram is controlled by the gear 57 and the clutch member 65 associated with it and is accomplished through the agency of the motor 44, pinion 56 and the arc-shaped rack 55. It may be desirable to employ a reversing gear in the gear train between the motor 44 and the pinion 56, so that the rotation of the pinion may be reversed without reversing the direction of the rotation of the motor. 110

The coke loosened by the breaker is conveyed across the floor of the coke oven by means of the members 12. It will, of course, be apparent that the supporting arms 38 of the members 12 are so proportioned as to length as to insure a raking action across the floor of the coke oven. The loosened particles of coke propelled by these members 12 are delivered to the apron 13 over which they move by gravity to the conveyer 14. The grill work 66 forming a part of the frame of this conveyer acts as a screen for the material moved across it by the conveyer cleats 70 and the small material, there-

fore, drops to the space between the rails of the track, whereas, the large commercial size coke is delivered by the hopper 15 to the car 16. In the drawings I have shown a lamp 87 mounted on the forward end of the carriage 9 and arranged to direct a beam of light into the coke oven. It will be apparent that this lamp may receive current from the line-wire 45 and that the swinging of the carriage directs the light in such a way as to aid the operator.

While I have described this invention as particularly applicable to a mechanism for clearing coke ovens, it will be apparent that apparatus embodying the invention may be used for other purposes and that various changes, additions, omissions, modifications and substitutions may be made in the apparatus illustrated without departing from the spirit and scope of the invention as set forth by the appended claims.

What I claim is:

1. In an apparatus of the character described, a frame, a carriage pivotally mounted thereon, a ram movably mounted on the carriage, a breaker mounted on the ram, material conveying devices mounted on the ram and movable longitudinally thereof, toward and away from said breaker, a power shaft journalled on said carriage, separated gear-trains for moving said ram, for actuating said breaker, and for swinging said carriage, and a separate clutch mechanism for operatively coupling each gear-train to said power shaft, propelling wheels on said frame, a conveyer on said frame for receiving material from said devices, and means for actuating said wheels and said conveyer.
2. In combination in a mechanism of the character described, a portable frame, a carriage pivotally mounted on the frame, a ram movably mounted on the carriage, a breaker mounted on the ram, material conveying devices mounted on the ram, movable there along, and operatively connected to said breaker, a driving motor mounted on the carriage, separate gear-trains for reciprocating the ram, for actuating said material conveying devices and said breaker, and for swinging said carriage and a separate clutch mechanism for operatively coupling each gear-train to said motor.
3. In combination in a mechanism of the character described, a frame, a carriage pivotally mounted on the frame, a ram movably mounted on the carriage, a breaker mounted on the ram, material conveying devices mounted on the ram, means for actuating said devices, a motor mounted on the carriage, gear trains associated with the motor for driving said means, said ram, and for swinging said carriage, and a separate clutch device for rendering each of said gear trains operative or inoperative.

4. In an apparatus of the character described, a frame, a carriage pivotally mounted thereon, a ram movably mounted on the carriage, and a breaker rotatably mounted on the rack, a motor mounted on the carriage, a shaft driven by the motor, separate gear trains for driving said ram, said breaker and for swinging said carriage, each driven by said shaft, and separate clutches for controlling the operation of each of said gear trains.

5. In an apparatus of the character described, a frame, a carriage pivotally mounted thereon, a ram movably mounted on the carriage, a breaker mounted on the ram, material conveying devices mounted on the ram and movable toward and away from said breaker, a motor mounted on the carriage, a power shaft driven by said motor, separate gear-trains for swinging said carriage, for actuating said ram, and for actuating said devices, and separate clutches mounted on said power shaft for rendering each gear-train effective and ineffective in transmitting power therefrom.

6. In an apparatus of the character described, a portable frame, a carriage, movably mounted on the frame, a ram movably mounted on the carriage, a breaker rotatably mounted on the ram, a power shaft journalled on the carriage, separate gear-trains mounted on the carriage for moving the carriage, for moving the ram, and for rotating the breaker, and a separate clutch between said power shaft and each of said gear-trains.

7. In an apparatus of the character described, a movable ram, a breaker carried thereby and adapted to be inserted by said ram into a coke oven through the door of the oven, means for actuating said breaker, for moving said ram to different positions and power actuated means for pulling material freed by the breaker across the floor of the oven and through the door thereof.

8. In an apparatus of the character described, a breaker mounted on a ram, power actuated means for actuating said breaker, and power actuated means for moving material freed by the breaker across the floor and through the door of the container in which the material is located.

9. In an apparatus of the character described, a portable frame, a carriage pivotally mounted thereon, a ram movably mounted on said carriage, a breaker carried by the ram, means carried by the ram for removing material freed by the breaker, and a motor mounted on the carriage, a motor driven shaft, and gear trains driven by said shaft for swinging the carriage, for actuating the ram and the breaker and for actuating the means carried by the ram.

10. In an apparatus of the character described, a portable frame, a carriage pivot-

ally mounted thereon, a ram movably mounted on said carriage, a breaker carried by the ram, means carried by the ram for removing material freed by the breaker, and a motor mounted on the carriage, a shaft on the carriage driven by the motor, clutch controlled gears driven by the shaft for swinging the carriage, for actuating the ram and the breaker and for actuating the means carried by the ram, a conveyer mounted on the frame for receiving material moved by the ram carried means, and motor driven means for actuating said conveyer.

In testimony whereof, I have hereunto subscribed my name this 8th day of April, 1920.

DAVID FERGUSON.
